AIR CIRCULATING SYSTEM FOR REFRIGERATOR CARS AND THE LIKE

William E. Van Dorn, Pasadena, Calif., assignor to Pacific Railway Equipment Company, Los Angeles, Calif., a corporation of California

Application July 9, 1940, Serial No. 344,509

3 Claims. (Cl. 98—6)

This invention refers to improvements in air circulation in transport vehicles. The invention is capable of general application to transport vehicles wherever air circulation is desired. But it has been designed particularly with reference to refrigerator cars and will therefore be described typically and illustratively in that application and use. In some of its aspects the invention is directed to improvements upon my invention entitled Air circulating system for refrigerator cars and the like, for which I filed application, Ser. 183,235 on January 3, 1938, now Patent No. 2,214,210, issued Sept. 10, 1940.

The general objects of the present invention are to provide an improved circulating system, including improvements both in the air impeller unit and its mounting and disposition relative to the car, and in the driving means for the unit. Although the driving means has particular utility in combination with the improved air impeller unit, it is also useful for driving any usual car accessory.

The detailed objects and accomplishments of the invention will best be gathered from the following description of preferred and illustrative forms of the system, and their functions. However, I may mention preliminarily that the improved system and devices of the present invention, have advantages, among other things, in their easy adaptability and applicability to refrigerator cars of all types and kinds, in efficiency of operation, in freedom from necessity of frequent service, in ease of servicing, and in adaptability to being driven either from the running gear of the car or by independent power.

In the accompanying drawings:

Fig. 1 is a fragmentary transverse section illustrating one form of my improved system applied to a refrigerator car, this view being taken as indicated by line 1—1 on Fig. 2;

Fig. 2 is a longitudinal section and side elevation of the parts shown in Fig. 1, being taken in the aspect indicated by line 2—2 of Fig. 1;

Fig. 3 is a section taken on line 3—3 of Fig. 1;

Fig. 4 is a detail section taken on line 4—4 of Fig. 1;

Fig. 5 is an enlarged detail section taken on line 5—5 of Figs. 2 and 4;

Fig. 6 is a diagrammatic section taken as indicated by line 6—6 on Fig. 3;

Fig. 6a is a section similar to that of Fig. 6 and showing a modified form of traction roller for the driving mechanism;

Fig. 7 is a plan, partially broken away in section, showing the structure and disposition of the air impeller unit which is shown in Fig. 1;

Fig. 8 is a transverse section, similar in aspect to the transverse section of Fig. 1, and taken as indicated by line 8—8 on Fig. 9, showing a modified form of driving mechanism;

Fig. 9 is a fragmentary longitudinal section taken on line 9—9 of Fig. 8;

Fig. 10 is a longitudinal section taken on line 10—10 of Fig. 8;

Fig. 11 is an enlarged detail section in a substantially horizontal plane taken on line 11—11 of Fig. 10;

Fig. 12 is an enlarged detail section taken on line 12—12 of Fig. 9;

Fig. 13 is an enlarged transverse section taken as indicated by line 13—13 on Fig. 2 and showing the application of the independent driving motor;

Fig. 14 is a section taken as indicated by line 14—14 on Fig. 13.

Referring first more particularly to Figs. 1, 3 and 7 I will first describe the improved form of air impeller unit and its disposition with relation to a car body. In these figures the car floor is indicated at 20, the two side walls at 21 and the ice bunker wall at 22. In typical refrigerator car construction there is an opening at 23 at the lower part of bunker wall 22, of a height about equal to the height of the lading floor above the car floor, and extending across the width of the car. The typical refrigerator car has two such ice bunker walls at opposite ends, and there are openings, similar to 23, in the upper portions of the bunker walls. The lading floor is usually in the form of a rack or racks having floor slats 24 supported on stringers 25 that rest on the car floor. And it is common practice that the floor racks are divided longitudinally at the center of the car, as indicated by the gap shown at 27 in Fig. 7; the two racks being hinged to the sides of the car, as indicated at 28 in that figure. It is desirable that the floor racks be liftable for cleaning and other purposes, and my impeller unit fully accommodates that desirable operation, as will be seen.

In applying my improved system to a car I preferably use two impeller units 30, each with its independent driving mechanism, in a position substantially over a truck or substantially over one of the wheel and axle units of a truck. The location of each impeller unit is therefore somewhat near an end of the car, and the two impeller units, acting in concert, set up a circulation throughout the whole interior of the car body. Each of the impeller units is installed in the space between the upper surface of the lading floor and the upper surface of the car floor proper; and the direct action of each of the units is to impel the air longitudinally along the space between the two floors.

The direction in which the air is thus impelled may be made to suit any desired type or direction of air circulation. For instance, the impellers may be so arranged and set that they both impel the air in the same longitudinal direction between the bar floors; in which case the air will circulate downwardly through one of the ice bunkers, longitudinally along the floor, upwardly through the other ice bunker and then longitudinally through the car above the floors to the top of the other ice bunker. In another type of circulation the two air impelling units may move the air in opposite directions between the two floors. Thus each impelling unit may act to draw air from the lower end of the adjacent ice bunker and impel it between floors toward the center of the car. The air then rises throughout the load and the central portions of the car and, in a double circulatory path, passes then to the upper parts of the ice bunkers and then downwardly through them. Without any limitation upon the invention this latter described circulatory path is the one which I think preferable. And when the impelling units are arranged for that type of circulation, the impelling units are not only counter-parts of each other, but, in their functions, are symmetric counter-parts. A description of one such unit, its mounting and disposition and its driving mechanism is therefore sufficient to a complete understanding of the invention.

In connection with what is said in the immediately foregoing I call attention to the fact that my improved system, and particularly the impeller units, are of such nature that they always move the air in the same directions with reference to the car regardless of the direction of car travel. The most effective circulatory paths may thus be chosen to suit the particular circumstances, the system may be installed to obtain the directions of circulation thus chosen, and the circulation directions will then remain unaffected by the direction of car travel.

The impeller unit includes a casing made up of a bottom plate 35, discontinuous side walls 36 and transverse partitions 37, which side walls and partitions are made up of bent metal sheets in a manner which will be understood from inspection of Fig. 7. The side walls and partitions are secured to the base plate by welded flanges 38. The arrangement is such that alternate spaces are provided between the several pairs of adjacent partitions for the reception of air impellers 39. Each of these impeller-receiving spaces is open at one side of the casing and closed by side wall 36 at the other side. In Fig. 3 the open side is to the right and in Fig. 7 at the top of the figure.

Impellers 39 of the radial blade type or radial blower are mounted upon a common shaft 40 mounted in bearings 41 which are in turn mounted upon the side walls 36. I use the term "radial blower type" to denote the type of impeller which impels the air outwardly with respect to the impeller axis, rather than along the axis as with a fan-type impeller. A suitable number of bearings is provided to support the shaft adequately, and each bearing is so mounted as to allow freedom for shaft alignment. As shown in Fig. 1, 42 represents the external race ring of a ball bearing carrying the shaft 40. This external bearing ring is carried in an internally recessed rubber ring 43, into which the external ring of the bearing is forced. The rubber ring is also externally recessed, and is forced into the carrier ring 44 of mounting bracket 44a which is mounted on side wall 36 of the casing.

Impellers 39 are preferably double in form and

comprise two sets of radial blades 45 which extend oppositely from a central mounting flange or web 46. Each impeller is preferably made in halves so as to be separable along a central axial plane, and is mounted upon the shaft by clamping bolts 47 which secure the two halves together. This structure makes for easy manufacture, as each impeller half can be accurately die-cast; and it also makes for ease in the removal and replacement of any injured impeller without having to dismantle the whole assembled impeller unit.

The direction of air movement through the impeller unit, as indicated in Fig. 7, is always the same regardless of the rotational direction of the impellers. Each partition 37 is provided with an opening 37a concentric with the adjacent impeller. The spaces between partitions 37 that are not occupied by the impellers, are open at the side of the casing opposite the side at which the impeller occupied spaces are open, as is clearly shown in Fig. 7. Air thus enters at one side of the casing in the space between two adjacent impellers, then flows longitudinally into the two adjacent impellers, and is then thrown out radially at the opposite side of the casing. The net result is that air travels through the whole impeller unit in the longitudinal direction indicated by the arrows in Fig. 3.

The whole impeller unit is placed transversely of the car, resting upon car floor 20. The lading racks are cut away to receive the impeller unit, and transversely extending screens 50 are secured to the ends of rack stringers 25 at opposite sides of the unit. These screens operate to screen out any solid material which might otherwise be carried by the air stream into the impellers and damage them.

Cover plates 51 and 51a are secured to the floor racks. These cover plates have depending side flanges 51b which are secured to and across the several stringers 25 of the two hinged floor racks, the covers being thus mounted at such an elevation that they fit down closely over the upper edges of side walls 36 of the impeller casing. To strengthen, the casing and to provide a better support for covers 51 and 51a, longitudinal angle bars 52 are extended along and welded to the upper edges of side walls 36. Thus the cover plates are secured to and supported at their edges by the floor racks, and in their normal positions are supported intermediately by side walls 36 and angles 52; so that the cover plates are effective to carry any load that may be placed upon them. And for load carrying purposes the upper surfaces of the cover plates are flush with the upper surface of the lading floor.

The cover plates interconnect the two sections of each lading rack at the points where the lading racks are cut away to accommodate the impeller unit; so that the two hinged lading racks may be raised each as a unit. To close the top of the impeller casing at the gap 54 between the adjacent ends of the two cover plates, a special local covering plate 55 is utilized. This covering plate 55 lies under cover plates 51 and 51a and has hooked flanges 55a which hook under the angle bars 52.

In the installation as here shown (as applied to existing cars) impeller shaft 40 extends through car wall 21 at one side. For this purpose an opening is cut through the car wall and lined with a tubular liner 57. The annular space between the shaft and liner 57 is sealed by some suitable means to prevent inflow of air at that point. The suitable device indicated at 58 is

composed of a series of discs alternately attached to the shaft and to liner 57. The outer end of shaft 40, external of the car wall, carries pulley 60 adapted to take V-belt 61. Pulley 60, as shown better in detail in Fig. 13, has an outer screw-threaded hub 62 adapted to take another pulley 63 for the independent motor drive which may be applied to shaft 40 when the car is not in motion, as will be hereinafter described.

In the form of driving mechanism shown in Figs. 1 to 6a, a transverse tubular mounting shaft 65 is mounted directly under the car floor with its inner end rotatably carried in a bracket 66 conveniently mounted on one of the longitudinal girders 67 of the car body. The outer end of mounting shaft 65 is rotatably carried in a bracket plate 68 secured to the under side of the car body in a position substantially flush with the outer side of the car wall. Just inside the bracket plate 68 an arm 69 is mounted at its upper end loosely around mounting shaft 65, so that although that end of arm 69 is thus restricted to a swinging motion, it is to a certain extent allowed universal motion. Arm 69 extends diagonally downwardly and at its other end is attached, preferably rigidly, to the outer end of the tubular shaft housing 70. A brace 69a is placed between housing 70 and arm 69. The purpose of this rigid, braced attachment is to enable arm 69, which is confined longitudinally at shaft 65—see Fig. 5—to confine the shaft housing 70 against movement longitudinal of itself. The inner end of shaft housing tube 70 has a pair of opposite perforated lugs 71 through one of which there extends the bent end 72 of an arm 73 rigidly mounted at its other end on mounting shaft 65. In its normal or average operating position the shaft housing 70 is preferably substantially parallel to mounting shaft 65. The lug 71 which is shown as unused in Figs. 1 and 3 is provided for use when the mechanism is set up at the end of the car opposite to that which is here being described.

Driving shaft 75 is carried in bearings 76 in a shaft mounting member which is here shown in the form of a tubular housing 70, the bearings taking end thrust as well as radial. At its outer end this shaft carries drive pulley 77 which aligns with pulley 60 and takes the V-belt 61. At its inner end the extended end of shaft 75 carries the hub 78 of traction roller 79. This traction roller, whose structure and form will be herein-after explained in detail, carries an external traction tire 80 of rubber or any other suitable material adapted to be frictionally driven by the periphery of car wheel 81.

To keep traction roller 79 in pressure contact with the car wheel, and also to put the desired traction tension on belt 61, a yielding pressure is exerted on shaft housing 70 at a point between traction wheel 79 and pulley 77, the spacing of the pressure application point between pulley 77 and traction wheel 79 determining the proportionate applications of the pressure to those respective members. As shown in the drawings, a coil spring 82, coiled about mounting shaft 65, is conveniently used for the purpose, the free end 83 of the spring pressing downwardly upon housing 70 at the chosen position, which is here shown as being closer to roller 79 than to pulley 77. The fixed end 84 of the spring (see Figs. 2 and 4) bears upwardly in a notch 85 in the lower end of an angle plate 86 which is secured to the bracket plate 68.

This angle plate 86 also has a vertical slot 87

in which handle 88 may be raised and lowered. The normal position of handle 88 is its lower position as shown in the drawings, but it may be raised and held in its upper position, shown in dotted lines in Fig. 2, by a pin 89 which may be inserted in the plate 86. The handle 88 has a loop 90 at its inner end loosely surrounding the mounting shaft 65, or the extension thereof which is formed by the stud 65a. A collar 91 surrounds shaft 65 and carries a lug 92. The collar, tubular shaft 65 and shaft stud 65a are all secured together and lug 92 is positioned appropriately, by a pin bolt 93. A head 65b which lies outside the bracket plate 68, acting in conjunction with the fixed collar 91 and the parts 69 and 90, limits longitudinal (axial) movement of shaft 65 and of the mounting arm 69. In the normal operating positions of the parts lug 92 is in such position that handle 88 lies below it with a sufficient clearance to allow the driving shaft 75 and traction wheel 79, and mounting shaft 65, the necessary amount of motion about the axis of shaft 65 for normal operation, without lug 92 coming into contact with handle 88. Such relation of the parts is shown in Fig. 4. When handle 88 is raised it comes into contact with lug 92 and rotates mounting shaft 65 in a clockwise direction in Figs. 2, 3 and 4. Arm 73 is correspondingly swung upwardly, lifting the inner end of shaft housing 70 and lifting traction roller 79 off car wheel 81. In this operation the outer ends of housing 70 and the driving shaft 75, and pulley 77, are not moved except to tilt them slightly about the universally loose mounting of arm 69 on shaft 65. Those parts can of course be lifted if desired to loosen the belt and put it out of tractive engagement with the pulleys. The parts can be locked in this position by use of pin 89, and traction roller 79 may then rotate freely to accommodate the independent power driving of the system, afterwards described.

The casing which encloses the belt drive and affords a mounting for the independent motor drive, is made up essentially of a removable cover plate 95, and an upper end wall 96 and side walls 97 which are preferably formed of a single piece of metal of Z-section cut and bent at the corners at 98. The rear flanges 99 of the Z-section are secured to the outer face of the car wall and to the outer face of bracket plate 68. The cover plate 95 has inturned flanges 100 along its longitudinal edges adapted to engage the outer flanges 101 of the side walls. The lower end of the cover plate is bent inwardly and then upwardly as shown at 102 in Figs. 1 and 2 to form a protective casing below the drive pulley 77; and bolts or pins 103 hold the cover in place. The cover may be easily removed by removing the bolts 103 and sliding the cover downwardly. Details of formation of the casing and its cover plate may be seen more readily in the horizontal sections of Figs. 12 and 14. Although Fig. 12 is illustrative of the modified form of driving mechanism, the casings for both forms of the mechanisms are the same and have therefore been given the same numerals in Fig. 12. The drawings show how the belt drive is arranged in a plane parallel and close to the car wall, and the enclosing casing is flat and shallow, projecting only a small distance from the wall.

Opposite the upper drive pulley 60 cover 95 has an opening 105 to facilitate attachment of the independent drive pulley 63. This pulley, as shown in Fig. 13, has an internally threaded hub

106 adapted to be threaded onto the threaded hub 62 of pulley 60. The direction of threading pulley 63 onto hub 62 is the same as the direction of drive by the independent drive motor M. Motor M has a drive pulley 107 of suitable size, and belt 108 drivingly interconnects pulley 107 with pulley 63. Motor M is mounted at its pulley end on a bracket 109 which has inturned flanges 110 forming sliding guides for the bracket and motor on the longitudinal edges of cover plate 95. Set-screws 111 may be used instead of one of the flanges, so that by retracting the set screws the motor bracket may be removed from the casing cover without having to slide it vertically over the end of the cover.

Whenever it is desired to drive the impeller unit from the independent motor M, it and the pulley 63 and belt 108 are put in place as shown in Figs. 13 and 14. Handle 88 is raised to the dotted line position in Fig. 2, and locked in that position. Raising the handle 88 rotates arm 13 about mounting shaft 65 and thus raises the traction roller 79 off car wheel 81. In this operation only that end of shaft housing 70 which is adjacent friction roller 79 (the left-hand end in Fig. 1) is raised. The other end of shaft housing 70 is allowed to remain substantially in the position of Fig. 1 by reason of the looseness of arm 69 at its mounting on mounting shaft 65. Thus the drive belt 61 is not disturbed by raising traction pulley 79, but remains at all times in proper contact with the two drive pulleys 60 and 77.

It is preferred that the independent motor drive be applied directly to the upper impeller unit shaft, as has been described. But it may be applied to the lower driving shaft, such as the shaft 70 that has been described, for the driving belt 61 is always in traction relation to its two pulleys.

In certain aspects of my invention, for instance those relating to the independent driving of the impeller unit, the normal drive from the running gear may be had in any suitable manner. I prefer however to take that drive by friction traction from a wheel on the running gear, and certain aspects of the invention relate to driving mechanism for that purpose. In that connection the wheel illustrated at 81 in the drawings may represent any wheel on the running gear. Preferably however it is the car supporting wheel, and further features of the invention have to do with utilizing traction drive from that wheel.

In the form of driving mechanism which has so far been described, the whole mechanism is mounted upon the car body, and a certain amount of relative lateral movement takes place between car wheel 81 and traction roller 79 when the truck swivels with relation to the car body in rounding curves, or shifts laterally with respect to the body. Figs. 6 and 6a show how the lateral component of the relative movement between car wheel and body is accommodated.

Referring first to Fig. 6, the tread of the car wheel is shown at 81a and its flange at 81b. The rubber or other tire 80 of the traction roller is made with tapering side surfaces 79a and preferably with a flat outermost peripheral surface 79b. The general sectional shape of the tire may be described as outwardly tapering, and preferably with a flat outermost periphery so as to provide a fairly broad traction surface for engagement with wheel tread 81a in normal operation. In normal operation, on straight-away track, the traction roller 79 occupies a relative position somewhat like that shown in Fig. 1 and shown 75

at position A in Fig. 6. Relative movement of the traction roller to the left (or the wheel 81 to the right) in Fig. 6 will cause its lefthand tapered surface 79a to climb wheel flange 81b to the relative position shown at B, and further relative movement of the traction roller toward the left makes the traction roller reach the relative position shown at C where its righthand tapered wall 79a is riding the inner surface of the wheel flange.

10 In all these relative positions the traction roller is in frictional driving engagement with either the car wheel tread or the flange. And on relative movement of the traction roller toward the right in Fig. 6, it may move relatively as far as

15 the position shown at D, where its lefthand tapered surface is still in frictional driving contact with the edge of the wheel tread. On return movement toward position A the lefthand tapered surface 79a will climb the outer edge of the wheel.

20 In the arrangement which is shown in Fig. 6, traction wheel 79 is prevented from dropping below the position D, in case it should pass further relatively to the right, by the lug 92 (see Fig. 4) engaging handle 88. Thus if the roller should under any circumstances pass further relatively to the right than position D, it will always be held at such a level relative to wheel tread 81a that upon reengaging the wheel tread it can climb back to position A. The friction

25 roller may thus at times go out of driving contact momentarily when the car is rounding short curves, but it will immediately move back into proper driving contact as the car passes beyond such a curve. The freedom which is allowed the traction wheel in a direction radial of the car wheel, allows the traction wheel to climb and descend the whole tread and flange contour of the car wheel.

30 In the arrangement shown in Fig. 6 the relative position C is substantially the limiting position of the traction roller toward the left. By choosing the normal relative position to be substantially that shown at A, it is found that ample relative latitude of movement is allowed without the roller having to reach or pass beyond the position C in its relative movement toward the left. And, as before stated, it may pass beyond its relative righthand position D without any harm.

35 To allow the roller to pass beyond its relative righthand position shown at D in Fig. 6, without losing driving contact with the car wheel, the arrangement shown in Fig. 6a may be used. Here the tread body of the traction roller 79c is the same as before described, but it has at its lefthand end a cylindric extension 79d, composed of the same substance as the tread. The diameter of this extension is such that its periphery clears wheel flange 81b when the roller tread 79b is riding on the wheel tread 81a. The length of cylindric extension 79d is such that when the roller reaches such a relative position as shown at D in Figs. 6 and 6a, the periphery of 40 79d will then ride on the wheel tread; but in lowering to the position D the end of extension 79d will clear the wheel flange. With 45 79d riding the wheel tread the traction roller may then move further out relatively toward the right without losing tractive engagement. The extension 79d also performs the office of limiting the downward movement of the traction roller in its extreme righthand position, and the limiting function of lug 92 may then either be eliminated, or arranged to act as a safety limit in the position of the traction roller below that shown at D.

Further, such a traction roller may also have an opposite cylindric extension such as shown at 79c in Fig. 6a, which will ride the periphery of flange 81b if the traction roller passes further relatively to the left than shown at C in Fig. 6.

In the swivelling movement between the car body and truck there is also a relative movement component in a longitudinal direction, between the car body and any wheel mounted on the truck axle except at the center. That relative longitudinal movement, as well as vertical movements of the body relative to the wheel, are taken care of by the action of spring 82, and the swinging action of arm 73, keeping the traction wheel in contact with the car wheel.

It will be seen from Fig. 3 that in normal position the radial line R , drawn through the centers of shafts 65 and 79, is approximately tangent to a circle concentric with car wheel 81. Swinging motion of traction wheel 79 about shaft 65 is therefore substantially radial of wheel 81. And when wheel 81 moves relatively longi-

titudinally, traction roller 79 swings (in Fig. 3) up and to the left or down and to the right; and the angularity of radius R and the length of arm 73 are such that in all its positions the spring pressed swinging movement of the traction roller is approximately radial of wheel 81. These described movements of traction wheel 78 and the inner end of drive shaft 75 and housing 10 are allowed by the universally loose mounting of their outer ends at the mounting of supporting arm 68 on mounting shaft 65. Preferably in normal position driving shaft 75 is substantially parallel to shaft 65 and the loose mounting of arm 68 allows all the necessary oscillations of shaft 75 about its normal position. In this preferred arrangement the length of arm 68 is substantially parallel to the radial line R of Fig. 3; and the direction of length of arm 68 is, as shown in Fig. 2, transverse of the direction between drive shaft 75 and impeller shaft 40, so that the downward swinging movement of arm 68 tightens belt 81. For that reason, as well as the fore-and-aft location of the impeller unit in the car body, the direction of shaft 40 from shaft 75 is angled somewhat from the vertical in the relative direction shown in Fig. 2—away from a vertical plane through the center of wheel 81.

The arrangement and mounting of the traction roller that have so far been described have been found to allow sufficient movement between the car wheel and body for relatively short cars travelling existing railway curves. For relatively long cars, where the angular swivelling movement between car body and truck is greater, and with trucks employing swing hangers for lateral motion, it is preferred to use the form of driving mechanism which is now to be described. This modified form of driving mechanism is shown particularly in Figs. 8 to 12. The impeller unit, its drive by the pulley 60, and its drive by independent drive motor M, are the same as before described.

In Fig. 8 the numeral 20 again designates the car floor and 81 the car wheel. Numeral 120 designates a part of the truck frame. The impeller unit which is driven by the mechanism shown in Fig. 8 is the same as before described, the belt 61 of Fig. 8 driving the impeller unit in the same manner. The casing enclosing the belt drive is made up in substantially the same manner as has been described.

A tubular bearing member 121 is mounted on 75

brackets 122 which are for convenience mounted upon a mounting plate 123 that is welded to truck frame 120. A carrier shaft 124 is rotatable in bearing sleeve 125 and carries a radial arm, 125 at its end adjacent car wheel 81. The outer end of this arm carries a bearing housing 126 within which there is an annular rubber or similar sleeve 127 in which the ball bearing 128 is carried. The outer race ring of the ball bearing is recessed into the inner surface of ring 127 as shown at 129, and that recessing enables the bearing to resist end thrust to a sufficient extent, although the bearing is free to take proper alignment to the extent that is necessary in the operation of the device. Bearing 128 carries a hub sleeve 130 through which the non-circular shaft 131 has slidable driving engagement. Traction roller 132 with its tread 133 is mounted on hub sleeve 130. Tread 133 is preferably of rubber or some good traction material and has a broad tread face which is made slightly conical to conform to the slightly conic shape of car wheel tread 81a. A coil spring 135 surrounds bearing tube 124 with its stationary end 136 bearing upon the mounting plate 123, and its moving end 137 hooks over the arm 125 to force the arm and the traction wheel toward the car wheel.

A handle 138 has its inner end 139 loosely mounted about mounting shaft 124, and is loosely held in place on the shaft by a collar 140. Collar 140 carries a handle engageable lug 141 in such a position as to allow sufficient angular movement of shaft 124 to accommodate normal movement of the traction roller in following the car wheel. The swinging movements of arm 125 to make roller 132 follow the wheel are, in this design, relatively small. Other than to accommodate wear, substantially the only movements of roller 132 are those due to relative vertical movement between the wheel and truck and those due to the longitudinal component of swivelling movements. And those due to the latter movements are again comparatively small because bearing 128 is close to roller 132. The traction roller may be raised off the car wheel by elevating handle 138, and may be held in that position by inserting pin 142 behind the handle.

The other end of shaft 131, as shown more clearly in detail in Fig. 12, carries a bushing sleeve 145, which in turn is carried by the ball bearing 146. Bushing sleeve 145 carries lower drive pulley 17a. Bearing 146 has its outer race recessed at 147 into the inner face of an annular rubber element 148 which is carried in a bearing housing 149 mounted on the outer end of an arm 150 whose inner end is rigidly mounted on a sleeve 151 rotatable upon pivot pin 152. Pivot pin 152 is mounted between the flanges of a U-shaped bracket 153 which is mounted, by welding or otherwise, on a bracket plate 154 which in turn is mounted, as by welding, on the under frame 155 of the car. The mounting of both the bearing carrying arms, and the mountings of the bearings in those arms, are such as to restrict drive shaft 131 against endwise displacement.

placement. A coil spring 166 surrounds sleeve 161 and has its fixed end 167 passing through a lug 158 which is mounted on the mounting bracket 152 (see Fig. 9). The free end 159 of the spring bears against bearing housing 149 in such a direction as to tend to swing arm 150 and bearing housing and that end of shaft 131 downwardly and to the right in Fig. 8. The radial length of arm

150 is transverse of the direction of belt drive 61 so that the action of spring 156 is to tighten the belt. And, due to the freedom which is accorded both bearings 146 and 128 to align themselves with shaft 131, spring 156 acts to keep the righthand end of shaft 131 in its illustrated position, and to keep belt 61 tight, when the left-hand end of shaft 131 moves to keep the traction roller in wheel engagement, or when the left-hand end of shaft 131 with traction wheel 132 are raised away from the car wheel.

In this latter described form of driving mechanism the traction roller 132 always occupies substantially the same position with relation to the car wheel, as regards lateral movement. Being carried by the truck frame, the traction roller has substantially no lateral movement relative to the car wheel. Lateral motion of the traction roller with relation to the car body is taken up by the sliding motion of drive shaft 132 through hub sleeve 130. And all other relative motions between the car body and truck are allowed by the universal freedom of shaft 131 to take, within the necessary limits, any relatively angled position that may be required. Traction roller 132, due to this type of mounting, keeps in tractive contact with the wheel tread regardless of the angle through which the truck and wheel may swivel with relation to the car body. This form of driving mechanism is therefore universally applicable, and is particularly applicable to long cars where the angles of swivelling action are large, and to trucks incorporating swing hangers for lateral motion.

It has been mentioned that the drawings show the air impeller and driving mechanisms in their design and arrangement as they are preferably applied to existing cars. On most existing cars there is sufficient room between the external surface of the car wall and the so-called "clearance line" to accommodate those parts of the driving mechanism that are here described as being located outside the outer surface of the car wall. And in applying the mechanisms to existing cars it is more convenient to place them external of the wall. However, the wall may be recessed to receive the upper parts of the drive mechanism; or the driving belt may even be run up through the car floor interiorly of the normal car wall and housed by an interior housing which may be regarded as an inward recessing of the car wall to a depth greater than the normal wall thickness. Such arrangements may be more easily applied to cars that are designed particularly to take my mechanisms, but they may also be applied to existing cars if desired or necessary. In any such arrangement the recessed wall may be regarded as the car wall for the purpose of my invention

and the definition of certain of its aspects in the following claims. Other aspects of the invention, such as those having to do with the impeller unit in itself or the lower driving mechanisms, will be understood to be not necessarily limited to any location relative to the car wall.

The claims following are directed to the subject matter of the air impeller structure and its relation to the car. Claims directed to the subject matter of the driving mechanism are made in my co-pending application, Ser. No. 498,536, filed August 13, 1943.

I claim:

1. In a refrigerator car having a car floor and a liftable lading rack spaced above the floor; an air impelled unit extending transversely across the car in the space between the planes of the floor and rack, said unit including casing walls; and a casing cover for the unit mounted on the lading rack in the plane of its upper surface and adapted to carry load.
2. In a refrigerator car having a car floor and a lading floor spaced above the car floor; an elongate air impeller unit extending lengthwise across the car in the space between the planes of the two floors, said unit including a casing having upper and lower walls, side walls and transverse partitions which enclose a series of spaces which are alternately open at opposite sides of the casing, the transverse partitions having aligned openings therethrough, an impeller shaft extending lengthwise through the casing and through the partition openings, and impeller elements of the radial blower type mounted on the shaft in alternate ones of the defined spaces.
3. In a refrigerator car having a car floor and a lading floor spaced above the car floor; an elongate air impeller unit extending lengthwise across the car in the space between the planes of the two floors, said unit including a casing having upper and lower walls, side walls and transverse partitions which enclose a series of spaces which are alternately open at opposite sides of the casing, the transverse partitions having aligned openings therethrough, an impeller shaft extending lengthwise through the casing and through the partition openings, impeller elements of the radial blower type mounted on the shaft in alternate ones of the defined spaces.
4. In a refrigerator car having a car floor and a lading floor spaced above the car floor; an elongate air impeller unit extending lengthwise across the car in the space between the planes of the two floors, said unit including a casing having upper and lower walls, side walls and transverse partitions which enclose a series of spaces which are alternately open at opposite sides of the casing, the transverse partitions having aligned openings therethrough, an impeller shaft extending lengthwise through the casing and through the partition openings, impeller elements of the radial blower type mounted on the shaft in alternate ones of the defined spaces, and journal bearings for the impeller shaft comprising bearing supporting brackets mounted on the side wall of the casing in spaces defined by the transverse partitions and not occupied by the impellers, and shaft bearings supported in the brackets through the medium of distortable sleeves.

WILLIAM E. VAN DORN.
